ATTORNEY.

UNITED STATES PATENT OFFICE.

ANNA M. FISHER, OF LOS ANGELES, CALIFORNIA.

COSMETIC APPLICATOR AND METHOD OF MAKING SAME.

Application filed July 21, 1928. Serial No. 294,487.

This invention relates to a new cosmetic applicator and method of making the same.

An object of the invention is to provide an improved appliance for removing the scaly portion of the cuticle from the face, hands, or other portion of the body if so desired, and at the same time to increase the circulation in the skin, thereby improving its condition and appearance.

10 Among the objects of the invention are the provision of an improved process or method of preparing the granular material which is to be applied to the skin; to impregnate the applicator with such materials in an improved manner, so to construct the applicator that it will be convenient to manipulate and will apply the granular cleansing materials to the skin in a more efficient and satisfactory manner, and in conjunction with other improved features to provide an ornamental, tasteful, and neat-appearing utensil for applying the granular material to the skin.

Other objects and advantages may herein-after appear.

25 Referring to the accompanying drawings which illustrate a preferred embodiment of the invention,

Figure 1 is a plan view of the applicator showing the face thereof opposite to that which is impregnated with the granular material.

Figure 2 is a section on line 2—2 of Figure 1.

Referring in detail to the drawings, the applicator consists of a plate, desirably a disk 5, of heavy rice paper or like material which has been impregnated with an oily substance, and having upon one face thereof a layer of granular material 6 the composition of which will be hereinafter described.

On the reverse side of the paper plate 5 is placed a layer of cotton felt, or other like fabric 7 which is pasted or glued in place upon said paper disk 5.

45 In order to supply said disk with a firm smooth periphery, the edge portion thereof is surrounded with over-edge stitching 8.

In constructing the appliance, the rice paper disk 5 is first soaked in a mixture of 50 almond oil and pure white vaseline the components of which have previously been blended together in any convenient manner. After having been soaked long enough in this compound to thoroughly impregnate said disk,

the surplus grease is wiped off. The disk is 55 then, if necessary, dried or baked to some extent in order to lessen the oily character of its surface, and then the granular coating 6 is applied. Three parts of almond oil to one part of vaseline are desirable proportions 60 for the oily mixture.

Said coating 6 is composed of finely ground cornmeal, fine almond meal, and fuller's earth. The almond meal is the most important ingredient of these three elements, and 65 may comprise three-fourths thereof. The cornmeal and fuller's earth may be in about equal parts.

Then the coating 6 of this granular material is spread on to the disk. The disk is 70 next placed in an oven and is baked for a short time, preferably two or three minutes at an average food baking temperature, say 400 degrees Fahrenheit. The disk is then steamed over water about five minutes. Then 75 it is again placed in an oven, not quite so hot as that used for the first baking, and is baked another two or three minutes. Then the mucilage is applied to the side opposite the layer of granular material and the cotton or 80 fabric layer 8 is applied to the mucilage coating. Then the blanketing or buttonhole stitching 8 is formed around the periphery to complete the disk.

The object of the felt layer 7 is to stiffen 85 the disk and to afford a suitable backing upon which the fingers may rest while the applicator is being rubbed upon the skin.

The thickness of the granular coat 6 is necessarily exaggerated in Figure 2 of the 90 drawings. Said granular coat is in reality so thin that the oil with which the plate is impregnated enters to some extent the granules of said coat and affects its action upon the portion of the skin to which the applica- 95 tor is applied.

I claim:

1. The process of making a cosmetic applicator which consists in soaking a paper plate in an oily substance, applying a coat of granular somewhat abrasive material to a face of said plate, and then baking said plate to cause said granular material to adhere thereto.

2. The process of making a cosmetic applicator which consists in soaking a plate of 100 material of substantially the consistency of heavy stiff paper in a composition composed of almond oil and vaseline, then applying a 105

coating of mixed almond meal, cornmeal, and fuller's earth to a face of said plate, then baking said plate, then steaming said plate and then again baking said plate.

5 3. As a new article of manufacture, a cosmetic applicator comprising a paper plate impregnated with a dried oleaginous compo-

sition and having a face portion thereof impregnated also with granular material which blends with the oily content of the plate, such 10 granular material thereby having its abrasive character mollified.

In testimony whereof I affix my signature.
ANNA M. FISHER.
